MACHINE FOR IMPREGNATING MATERIAL
WITH LIQUIDS

Leroy A. Kauffman, Washington, D. C.

Application November 18, 1946, Serial No. 710,551

4 Claims. (Cl. 91—12)

(Granted under the act of March 3, 1883, as
amended April 30, 1928; 370 O. G. 757)

1

The invention described in the following specification and claims may be manufactured and used by or for the Government for governmental purposes without the payment to me of any royalty thereon.

The present invention relates to machines for impregnating material with a liquid and more particularly to machines for force feeding one or more liquid compounds into materials such as fabrics, paper, leather and the like.

As an example of one application of the invention, the machine can be employed for feeding waterproofing compounds such as liquid latex under pressure across the entire width of a progressively fed sheet of material such as cotton duck whereby the material becomes permeated with the latex for increasing its strength while making it water and mildew proof. Treated fabrics of this type are particularly useful for producing all types of tarpaulins, gun covers, vehicle covers, tents and as a general substitute for waterproof duck as formerly produced, canvas or imitation leather. By using a colored liquid or liquids the material may be colored by the impregnation as well as striped, if desired.

The principal object of the present invention is to provide a machine for force feeding liquid or liquids across the entire width of a sheet of material positioned contiguous thereto.

A further object of the present invention is to provide a machine for controlling the delivery under pressure of one or more colored liquid compounds over an entire face of a progressively fed sheet material in such manner as to produce a solid color or longitudinally striped effect in various colors on the material as desired.

Another object of the invention is to provide a machine for feeding liquid compounds under pressure to a material which machine is of a simple construction and operation, has a minimum number of working parts, can be readily and easily cleansed, and is economical to produce.

Other objects of the invention will be in part obvious and in part pointed out in the following detailed description thereof based on the accompanying drawing in which;

Figure 1 is a side sectional elevation of a machine according to the present invention taken on line 1—1 of Figure 3,

Figure 2 is a partial side sectional elevation taken on line 2—2 of Figure 3,

Figure 3 is a top sectional elevation taken on line 3—3 of Figure 2,

Figure 4 is an enlarged detailed sectional view 55 Said reservoir 2 and openings 3 have parti-

2

of a portion of the machine as taken on line 4—4 of Figure 1, and,

Figure 5 is a perspective view of a two piece bearing and separator block forming a part of the invention.

Referring now more specifically to the accompanying drawings wherein similar members are designated by like reference numerals, 1 indicates a liquid compound supply head consisting of an 10 open end reservoir 2 connected by an elongated opening 3 formed in its base, to a pair of diametrically opposed semi-circular and longitudinally extended recesses 4 and a flat base 5 extending at right angles from said reservoir 2. 15 A slit 6 is formed through said base 5 along the bottom of said recesses 4 and is positioned in line with said opening 3 of said reservoir 2.

Positioned longitudinally of each of said recesses 4 is one of a pair of shafts 7 which are 20 suitably journaled in the detachable end walls 8 of said head 1. Each of said walls 8 being retained against said head 1 by a pair of bolts 12 passing through openings in said walls and screwed into threaded recesses in said head 1.

25 One end 9 of one of said shafts 7 extends through its corresponding side wall 8 and is surrounded at that point with a packing 10 to prevent leakage of fluid from within said head 1. Said end 9 has a multi-speed pulley 11 connected thereto 30 for receiving an endless belt connected to any suitable power means (not shown) whereby said shaft can be rotated at various speeds as desired.

Positioned across said opposing recesses 4 are a plurality of spaced separator bearing blocks 15 35 each consisting of an upper half-section 16 and lower half-section 17 normally retained together by a plurality of pins 18 positioned in openings 19 formed in the end portion of said sections 16 and 17.

40 The exterior face 20 of each end portion of said blocks 15 is formed and sized to exactly fit into and completely extend laterally across its corresponding recess 4 forming a partition therein. Further, the opposing faces of the sections 16 and 17 of each block 15 have semi-circular recesses 21 and 22 formed therein with the mating recesses each forming a bearing for its respective shaft 7 rotatably mounted therethrough.

Between each pair of said blocks 15 there is 45 fixedly mounted on each shaft 7 a roller gear 25 with the opposing gears 25 of both shafts 7 intermeshing as indicated in Figure 1. Each of said gears 25 is sized so that its addendum circle is very close to the wall of its respective recess 4.

tions 30 mounted therein over each of said blocks 15 dividing said head 1 into a plurality of reservoirs. Similarly a partition 31 is mounted in slit 6 beneath each of said blocks 15 defining a series of outlets for fluid from said reservoirs. As best noted in Figure 4, each partition 31 has a triangular cross-sectional configuration with its apex 32 positioned for bearing against the material 35 being treated.

Positioned beneath said base 5 is a platen 40 shown as a flat member, but which can equally as well be of the round rotatable type, if desired. Said head 1 is adjustably mounted by any suitable structure (not shown) on or above this platen 40.

In the operation of the present machine the fluid to be employed is placed in said reservoir 2 and the material 35 to be treated is progressively moved either by hand or suitable mechanism, past slit 6 over platen 40. Said head 1 and platen 40 are adjusted relative to one another to just permit the movement of said material 35 therebetween. As an example of one way of accomplishing the adjustment, bolts 41 mounted with each bolt extending through an opening formed in each corner of said base 5 and screwed into threaded recesses formed in platen 40, can be tightened or loosened as desired to determine the space for material 35 between said base 5 and said platen 40. At the same time pulley 11 is rotated causing shaft 7 and gears 25 to be rotated. The intermeshing gears 25 will draw the fluid compound from said reservoir 2 through opening 3 and force the same through slit 6 into the material 35 as it passes therebeneath. The speed of rotation of said gears 25 which depends on which part of pulley 11 is used, determines the amount and force of the fluid employed and can be adjusted by changing the position of the belt on said pulley 11.

It is contemplated that the width of the head 1 will extend completely across the width of the material being impregnated. As best shown in Figure 3 the end blocks 15 are positioned relatively close to the end walls 8 and the gears 25 positioned therebetween are shorter than the other gears employed. In this manner the escape of fluid around the end of the gears is minimized preventing a loss of pressure in the rest of said head 1.

To obtain a striped effect on the material being treated it is only necessary to put color impregnating liquids in the reservoir 2 with a liquid of a different color in between each pair of said partitions 30. The various colored liquids will then be fed between the corresponding blocks 15 and partitions 31 directly to the material thereunder.

After use of the machine, it can be cleansed very readily by unscrewing bolts 12 of one side and withdrawing the corresponding wall 8 and the accompanying shafts 7, blocks 15 and gears

25. These members are thereby made available for cleaning. The interior of the head can then be readily cleansed through the open end of said reservoir 2.

5 It is readily understood that the machine is capable of considerable modification and any changes thereto that come within the scope of the appended claims are deemed to be part of the invention.

10 What is claimed as new is given in the appended claims.

I claim:

1. A machine for impregnating material with liquids, comprising, a head having an elongated gear pump cavity in its lower portion, a flat base, there being a slot in the bottom of said cavity, opening through said base, a pair of spaced parallel shafts journaled in said cavity, a first set of axially spaced gears fixed on one said shaft, a second set of axially spaced gears fixed on the other said shaft, each gear of one set meshing with a corresponding gear of the other set, a pair of complementary bearing sections fitting in the space between each pair of intermeshing gears 25 and the next axially spaced pair, said sections being shaped to closely fit the cross sectional area of said cavity, and means forming a liquid reservoir above said cavity, there being a passageway from the bottom of said reservoir to the top of said cavity.

2. A machine as recited in claim 1, said cavity being closed at its ends by plates each having bearing apertures for the adjacent ends of said shafts, and means removably securing said plates 35 to said head, whereby on removal of one plate, the entire assembly of shafts, gears and bearing sections may be withdrawn as a unit in a direction axially of said shafts.

3. A machine as recited in claim 1, a plurality 40 of partitions in said reservoir, each partition cooperating with a respective pair of bearing sections to divide said cavity and reservoir into liquid-tight compartments, spaced axially along said shafts.

4. A machine as recited in claim 1, and a block 45 snugly fitting said slot beneath the lower one of each said pair of bearing sections, said block having its upper face abutting said lower section and its lower face flush with the flat base of said head.

50 LEROY A. KAUFFMAN.
